COMBINED MAIL BOX AND SUPPORT THEREFOR

Louis K. Loewenstein, Elkins Park, Pa.

Application October 22, 1956, Serial No. 43,457

Term of patent 14 years

(Cl. D74—9)

Fig. 1 is a side elevational view of a combined mail box and support therefor showing my new design;

Fig. 2 is an end elevational view thereof as it appears looking at the right of Fig. 1; and

Fig. 3 is a top plan view thereof.

The opening in the box is conventional and is located at the left hand or wide end of the box as viewed in Figs. 1 and 3.

I claim:

The ornamental design for a combined mail box and support therefor, substantially as shown and described.
